UNITED STATES PATENT OFFICE.

WALTHER WOLFF, OF BERLIN-KOPENICK, GERMANY, ASSIGNEE TO GENERAL ELECTRIC COMPANY, A CORPORATION OF NEW YORK.

AMPLIFIER CONNECTION.

Application filed April 7, 1925, Serial No. 21,429, and in Germany May 23, 1924.

My present invention relates to operating connections for thermionic amplifiers, and more particularly to means for closing or opening a heating circuit for the cathodes of thermionic amplifiers from a distant point.

In some cases it is found desirable, where thermionic amplifiers are employed in long distance telephone lines, to have means provided whereby an operator who controls the transmission over the line may be able at will to close or open the heating circuit for the cathodes of amplifiers which are located at an intermediate point in the telephone line.

The object of my invention is to provide a simple and reliable means whereby this result may be accomplished.

I have found that the object of my invention may be readily attained by providing means for closing the heating circuit which is responsive to current of one particular character, and a means for opening the heating circuit which is responsive to current of a different character.

The novel features which I believe to be characteristic of my invention are set forth with particularity in the appended claims. My invention itself, however, both as to its organization and method of operation, will best be understood by reference to the following description taken in connection with the accompanying drawing in which Fig. 1 shows diagrammatically a circuit arrangement adapted to carry out my invention; and Fig. 2 shows a second circuit organization which may be employed in cases where trunk lines are used in phantom to provide additional talking circuits.

The arrangement shown in Fig. 1 comprises the telephone trunk line 1, 2, which is connected at points 3, 4 to the amplifying system. The trunk line is coupled by means of a transformer 5 to the amplifiers. Between the points 6, and 7, in the secondary circuit of transformer 5 the winding 8 of an alternating current relay is connected. The filaments 9 of the amplifier tubes are connected to a local battery 10 through contacts 11 and 12 of the two relays having windings 13 and 14. For convenience in description and to simplify the drawing, the connections of the amplifier input and output whereby the voice currents received over the lines 1 and 2 are amplified, have been omitted.

When the operator at a distant point wishes to place the amplifier in operative condition for amplifying speech current, an alternating current impulse is transmitted over the line 1, 2. This operates relay 8 and closes the contact at 15. This closes the circuit of a relay 16 through a battery 17. The relay 16, being energized, closes a contact at 18 and thus closes the heating circuit for the filaments 9. At the same time the relay 13 is energized and closes contact at 11, thereby holding the heating circuit closed after the contact at 18 has been opened upon the cessation of the alternating impulse. The relay 13 holds the heating circuit closed.

When the conversation is terminated and the operator desires to open the heating circuit, a direct current impulse is sent over the trunk line 1, 2. This direct current impulse energizes relay 14 and opens the contact at 12, the armature of relay 14 being biased so that the contact at 12 is normally closed. As a result the heating circuit is opened, the relay 13 becomes deenergized, contact at 11 is broken and the amplifier connections are restored to their original condition.

If desired, additional contacts 19 and 20 may be provided on relay 16 for the purpose of closing suitable circuits to transmit the call to a more distant station. For the same reason, additional contacts 21 and 22 may be provided on the relay 14 to transmit impulses to distant stations for opening the heating circuits.

In the arrangement shown in Fig. 2 connections are indicated whereby the heating circuits of the amplifying tubes 23 and 24 of two trunk lines may be controlled and also the heating circuit of amplifier tubes 25, which are employed in phantom circuit, may be controlled. The trunk lines are indicated at A, B and C, D, and the phantom line at E, F. The control of the heating circuits for the amplifiers employed in the trunk lines A, B and C, D is brought out in the manner described in connection with the arrangement shown in Fig. 1, provisions having been made whereby the operation may be controlled from either direction. The control of the heating circuit for the amplifier tubes 25 in the phantom circuits is as follows:

When an operator at a distant station wishes to put in operation the amplifiers

for the phantom circuit, an alternating current impulse is sent out over the phantom line. This current flows through the condensers 26 to a point 27, and from thence 5 it flows through the primary of transformer 29 to the point 30, thence through condensers 31 and the primary windings of the transformer 5 back to the distant station. The relay 32, which is connected to the secondary 10 of transformer 29, is energized and closes the heating circuit of the amplifier tubes 25 in the manner described in connection with Fig. 1.

When the conversation over the phantom 15 circuit has been concluded the operator sends a direct current impulse over the phantom circuit. This impulse flows through the connecting conductors 33 to the mid-point 34 in the winding of relay 35, thence through 20 the winding of relay 36 to the midpoint of the winding of relay 37, thence through windings of relay 37, and connecting conductors 38 to the conductors of line C. As 25 a result relay 36 is energized, opening the contact at 39, and thus opening the heating circuit for amplifier tubes 25. Since this direct current flows differentially through the windings of relays 35 and 37, it does not 30 in any way interfere with the operation of the amplifiers in the trunk line circuits.

What I claim as new and desire to secure by Letters Patent of the United States is:—

1. The combination in a thermionic amplifier system of means whereby a circuit for 35 supplying heating current to the cathode of an amplifier from a local source of current may be closed by means of a current impulse of one form supplied from a distant point, and a different means whereby the circuit 40 may be opened by means of a current impulse of a different character from the first which is also supplied from the distant point to a circuit which has different characteristics from that to which the closing 45 impulse is supplied.

2. The combination in a thermionic amplifier system of means whereby a circuit for 50 supplying heating current to the cathode of an amplifier may be closed by means of a current impulse of one form supplied from a distant point, means in addition to the closing means for holding the circuit closed, and means whereby the circuit may be

opened by means of a current impulse of a different character from the first which is 55 also supplied from the distant point.

3. The combination in a thermionic amplifier system of means whereby a circuit for 60 supplying heating current to the cathode of an amplifier may be closed by means of an alternating current impulse, supplied from a distant point, and means whereby the circuit may be opened by means of a direct current impulse which is also supplied from the distant point. 65

4. The combination in a thermionic amplifier system of a relay adapted to effect the closing of a circuit for supplying heating current to the cathode of an amplifier and a second relay adapted to open the heating 70 circuit, circuit means for supplying to one of said relays an alternating current impulse transmitted from a distant point and circuit means for supplying to the other relay a direct current impulse transmitted from the 75 distant point.

5. The combination in a thermionic amplifier system of a relay adapted to effect the closing of a circuit for supplying heating current to the cathode of an amplifier and 80 a second relay adapted to open the heating circuit, circuit means for supplying to one of said relays an alternating current impulse transmitted from a distant point and circuit means for supplying to the other 85 relay a direct current impulse transmitted from the distant point, and a third relay for holding the heating circuit closed until the second relay has been operated.

6. The combination in a thermionic amplifier system of an incoming line, a relay connected in a circuit which is conductively connected to said line, a second relay connected in a circuit which is inductively connected to said line, a circuit for supplying heating current to the cathode of an amplifier, means whereby said heating circuit may be closed by a current impulse transmitted over said line to one of said relays, and means whereby said heating circuit may be opened by a current impulse transmitted over said line to the other relay. 95 100

In witness whereof, I have hereunto set my hand this 20th day of March, 1925.

WALTHER WOLFF.
